(57) **CLAIM**

The ornamental design for a power module package, as shown and described.

DESCRIPTION

FIG. 1 is a perspective view of a first embodiment of a power module package showing our new design;

FIG. 2 is a top plan view thereof;

FIG. 3 is a bottom plan view thereof;

FIG. 4 is a front view thereof;

FIG. 5 is a rear view thereof;

FIG. 6 is a side view thereof;

FIG. 7 is an opposite side view thereof;

FIG. 8 is a perspective view of a second embodiment of a power module package showing our new design;

FIG. 9 is a top plan view thereof;

FIG. 10 is a bottom plan view thereof;

FIG. 11 is a front view thereof;

FIG. 12 is a rear view thereof;

FIG. 13 is a side view thereof; and,

FIG. 14 is an opposite side view thereof.

Evenly spaced broken lines depict unclaimed portions of the environmental structure, and form no part of the claimed design. Dot-dash lines depict boundaries of the claimed design, and form no part of the claimed design.

The shading in FIGS. 1-14 indicates claimed surface areas on the power module package.
